UNITED STATES PATENT OFFICE.

FRED G. HOOKE AND JAMES J. FLYNN, OF LOWELL, MASSACHUSETTS.

SOLE TRIMMING AND POLISHING WHEEL.

Application filed July 29, 1925. Serial No. 46,745.

To all whom it may concern:

Be it known that we, FRED G. HOOKE and JAMES J. FLYNN, citizens of the United States, residing at Lowell, in the county of

- 5 Middlesex and State of Massachusetts, have invented certain new and useful Improvements in Sole Trimming and Polishing Wheels, of which the following is a specification.
- 10 In the manufacture of shoes, there is a type in which a material known as crêpe is used for the outer sole. This material is either rubber or a composition of rubber which is resilient, and of such consistency
- 15 that while it can be easily cut it is difficult to make a finished edge.

It is generally cemented or vulcanized to the bottom of the shoe and not stitched.

- In order that it shall be firmly attached it 20 is found necessary to use an intermediate sole of such composition that it can be stitched to the upper, and so that the outer sole can be cemented to it.

- To provide a suitable finished appearance, 25 the side of the outer sole and the other soles must lie in the same lines, and it is desirable that the bottom edge of the outer sole should be rounded.

- On account of the great number of styles, 30 and the number of sizes of shoes, it is necessary or customary to use a blank for the outer sole which is larger all around than the other soles, and than the finished size, and after this is attached by suitable cement or vulcanized, to trim off the excess at 35 the outer edge, and then polish the edge so that it will conform to the size of the intermediate sole.

- In finishing, it is necessary to avoid injury 40 to the upper.

- The present methods known as rough-rounding, edge setting, and edge trimming, include the cutting off the excess by hand, and then filing or grinding down, after 45 which a polish is put on by a wooden wheel.

- With our invention, after the first rough trimming, or rough-rounding, the trimming and polishing are combined in one process in which the leather and the crêpe sole are 50 finished together.

- To avoid injury to the upper, we prefer to use a separate roll for the heel which is generally thicker, but we round the edge of the heel on the wheel used for finishing the rest 55 of the outer and the inner soles.

Our invention substantially is a trimming

and polishing wheel which will polish the outer rim or side, and round and polish the bottom edge quickly and efficiently, and which will also keep the material clean.

We do this substantially by covering a wooden roll with compact felt, in which is an annular groove, and by tightly gluing or cementing while wet, a strip of emery cloth, with the emery on the inside, to this 60 felt. In this way a small part of the emery works through the cloth, but there is very little fly, and it is generally kept clean.

Besides this, there is none of the tendency to bounce off such as there is with a 70 wooden roll.

In the drawings, Fig. 1 is a side elevation of a shoe as it appears when the outer sole has been attached, but before it has been 75 trimmed.

Fig. 2 is a sectional view on the line 2—2 of Fig. 1 as viewed from the right.

Fig. 3 is a plan view of a form of intermediate sole which we prefer to use showing the false stitching, and with filling.

Fig. 4 is a plan of the toe part of a shoe with part of the edge of the outer sole cut off, but before it is trimmed.

Fig. 5 is a side elevation showing our 80 trimming and finishing wheel.

Fig. 6 is a section thereof on line 6—6.

Fig. 7 is a plan view of our trimming wheel with a shoe in position as it is being 85 trimmed and polished.

Fig. 8 is a front view of a stand with a heel trimming roller and a finishing roller on the same shaft.

Fig. 9 is a detail of our wheel.

In the drawings, F represents the upper of a shoe, to which by means of what is known as McKay through and through stitching 10 is stitched an intermediate sole A which may be an imperforate sheet of leather, or which preferably is of the skeleton type indicated in Fig. 3, so cut out at 90 20 as to form substantially a skeleton front part and shank, while the heel 22 is not cut out. This can be filled with composition 30 of a well known character.

An inner sole H may be used inside the 105 shoe, or where a skeleton intermediate sole is used, it may be stitched in as shown in Fig. 2, at 10.

To this intermediate sole A, preferably by means of cement, and also attached thereto 110 by the stitching 10 is a retaining sole B made of suitable fiber or leather. It should be

of such material that a thin holding sole C of the crêpe material can be firmly vulcanized thereto.

The stitches 10 extend through the soles 5 A, B and C.

The outer sole D of the crêpe material may be formed with a low heel 12, and is attached by cement to the sole C. It may be vulcanized thereto.

10 When this is done, a rim of the outer sole D projects as shown in Fig. 2, and this must be cut off by a hand knife or in any suitable way to be nearly even with the outer side of the soles A, B and C. To trim and polish 15 the side of this outer sole D, we use a wheel M.

This wheel M may be formed on a metal core 40 to which is permanently attached the wooden section 41, and the section 42 is attached by means of a tightening screw 43.

Around the circumference, we cement a strip of thick, compact felt L, and out of this we cut an annular groove of right angular cross section 50.

20 25 We then take a strip of emery cloth P, on one side of which is the emery 53, and after wetting this we glue it with the emery side in, around the felt band L.

The ends of the emery cloth may be 30 brought down in together between two wooden sections 41 and 42, which are then brought tightly together by means of screw 43.

When the emery cloth dries, it shrinks on 35 to the periphery of the wheel, and at the inside edge of the annular groove 50 will become rounded as shown between the vertical and horizontal walls 55 and 54.

40 After the outer sole has been properly trimmed, the side of the composite sole is brought up against the wheel M in the man-

ner shown in Fig. 9 so that the horizontal wall 74 of the emery cloth P will engage the edge of the sole while the rounded part 70 between the horizontal wall 74 and vertical wall 75 will round off the outer bottom edge 17 as desired.

The glue in the emery cloth is usually sufficient to stick the cloth to the felt and the weave of the cloth is open enough to allow some of the emery to go through and more to gradually work through. The cloth being wrong side in, our wheel is very clean and does not soil the shoes.

We prefer to use a stand such as R in Fig. 8 with bearings 60, 60, for a shaft 61, driven by a pulley 62. One end of shaft 61 carries a wheel M and the other end a wheel S, with no groove in its curved face. Wheel S is of wood with a felt periphery 69 covered with emery cloth 63 stuck to the felt face downward, and we use this for trimming and polishing the heel part which is thicker than the sole.

65 We claim:

1. In a shoe sole trimming and polishing wheel the combination with a cylindrical body; of a felt band attached to the periphery thereof, said felt band having an annular groove of substantially right angular cross section; and a strip of emery cloth having emery on the inner side, which is cemented and shrunk on to the felt band.

2. In a shoe sole polishing wheel the combination with a cylindrical body; of a felt band attached to the periphery thereof; and a strip of emery cloth having emery on the inner side, which is cemented and shrunk on to the felt band.

FRED G. HOOKE.
JAMES J. FLYNN.
